PORTABLE HOIST

Robert G. Le Tourneau, Peoria, Ill., assignor to
 R. G. Le Tourneau, Inc., Stockton, Calif., a corporation of California

Application December 18, 1942, Serial No. 469,442

6 Claims. (Cl. 214—65)

This invention is directed in general to a portable wheel-supported hoist of heavy duty type, and in particular the invention provides an auxiliary hoist for use in connection with a mobile elevator or utility truck, as shown for example in U. S. Letters Patent No. 2,279,832, issued April 14, 1942.

The main purpose of the present invention is to provide a heavy duty portable hoist which comprises the combination of the upstanding wheel-supported elevator frame assembly of the mobile elevator shown in the above identified patent, and a separate upstanding wheel-supported hoist frame assembly detachably and swivelly connected to said elevator frame assembly in trailing relation.

A further object of this invention is to provide a hoist as in the preceding paragraph in which said hoist frame assembly includes a horizontal top beam disposed a substantial distance above the ground, said beam being rigidly secured to and projecting forwardly from an upstanding portion of said hoist frame assembly, and being pivoted at its forward end on the elevator frame assembly for relative horizontal swinging movement; there being a cable actuated hoist unit depending from said top beam intermediate its ends, the pull cable for said hoist unit being connected with a power winch mounted on the mobile elevator and driven from its engine.

An additional object of this invention is to provide a heavy-duty high clearance portable hoist which comprises a pair of longitudinally spaced, upstanding and relatively tall frame assemblies, a horizontal top beam extending between said frame assemblies, said top beam being rigidly secured to one of said assemblies and pivotally secured to the other thereof for relative horizontal swinging movement, and a cable actuated hoist unit depending from the top beam intermediate its ends; said other frame assembly being arranged in draft connection with a tractor which includes a power winch, the pull cable of the hoist unit being operatively connected to said winch.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference

indicate corresponding parts in the several views:

Figure 1 is a side elevation illustrating the auxiliary hoist as arranged in connection with the mobile elevator.

Figure 2 is a fragmentary transverse sectional elevation on line 2—2 of Fig. 1, looking forward.

Figure 3 is a transverse sectional elevation on line 3—3 of Fig. 1, looking to the rear.

Referring now more particularly to the characters of reference on the drawings, the auxiliary hoist is designed for detachable connection with the mobile elevator shown in United States Letters Patent No. 2,279,832, which includes an upstanding elevator frame assembly indicated generally at 1, said assembly being supported at its lower end by transversely spaced ground engaging wheels 2. As in the identified patent, the elevator frame assembly is connected in trailing relation with a two-wheel tractor 3 by a vertically rigid horizontally swiveling draft connection indicated generally at 4.

The tractor 3 includes a two-drum power winch 5 mounted on and projecting rearwardly therefrom; said power winch being of a type commonly employed on tractors. A cable 6 is connected at one end with one drum of the power winch 5 and leads therefrom to the elevator frame assembly, where it is connected with suitable means to effect raising and lowering of a vertically movable elevator frame 7 upon rotation of the drum in one direction or the other. When not in use with the hereinafter described auxiliary hoist, the elevator frame 7 is moved up and down through the medium of cable 6 to raise or lower a load carried upon load supporting arms 8 which project rearwardly from the lower end of the elevator frame 7.

The above structural details of the mobile elevator are described in detail in the identified issued patent.

The auxiliary hoist which is adapted for detachable connection with the mobile elevator comprises the following:

A horizontal longitudinally extending top beam 9 is fixed at its rear end in connection with an upstanding A-frame 10, the legs of which are disposed in transversely spaced relation. This A-frame is supported by transversely spaced ground engaging wheels 11 rotatably mounted on the lower ends of the legs of said frame.

At its forward end the top beam 9 is pivotally connected, for relative horizontal swinging movement, with a horizontal transversely extending cross beam 12 which the elevator frame 7 includes at the top. The pivotal connection be-

tween the forward end of the top beam 9 and cross beam 12 comprises a vertical pin 13 fixed on and upstanding from an attachment plate 14 secured to the cross beam 12 centrally of its ends. The forward end of the cross beam 9 is fitted with a vertical bushing 15 into which the pin 13 removably projects from below.

The height of beam 9 from the ground is such as to be slightly above cross beam 12 when frame 7 has been raised a predetermined distance from its normal lowered position, and in the present embodiment is approximately sixteen feet. To engage the pin 13 in the bushing 15, the elevator frame 7 is run upwardly to the necessary extent by means of the cable 6, and is thereafter held in such position by suitably braking the corresponding drum of the power winch 5. Also, when the elevator frame 7 is thus raised, the load supporting arms 8 are disposed a substantial distance above the ground and are clear of the load which the auxiliary hoist is to lift.

The lifting mechanism of the auxiliary hoist comprises a multiple sheave block and tackle unit 16, the upper block of which is secured to and depends from the horizontal top beam 9 substantially centrally of its ends; the lower block 17 of the block and tackle unit 16 including a downwardly projecting lifting hook 18.

A direction changing sheave 19 is mounted on the top beam 9 adjacent the upper block 20 of the block and tackle unit 16, and the pull lead 21 of said block and tackle unit extends therefrom over sheave 19 and thence about direction changing sheaves 22 and 23 secured, respectively, on the forward end of top beam 9 adjacent pin 13, and on the draft connection 4 above the winch and adjacent the vertical axis of said connection. From the sheave 23 the pull lead 21 is connected with the other drum 24 of the power winch 5. As is apparent, rotation of drum 24 in one direction or the other will effect raising or lowering of the lower block 17 and hook 18 of the block and tackle unit 16.

In use, the tractor 3 is maneuvered until the load to be lifted is straddled by the frame structure which includes elevator frame assembly 1, frame assembly 10, and horizontal top beam 9, and which forms in effect a rectangular arch. Thereafter the hook 18 is suitably connected with the load to be lifted, and the drum 24 of the power winch 5 rotated in a direction to raise block 17 and hook 18. When the load has been lifted to a position clear of the ground and drum 24 is braked and the tractor 3 is then in motion, the hoist structure and the lifted load trails thereafter.

By reason of the pivotal connection between the top beam 9 and elevator frame 7, the tractor is steerable relative to the hoist frame assembly, and particularly the rear wheels 11. This is a desirable feature, as it facilitates loading, transporting, and unloading of the object to be lifted.

The structure is such that objects of great size and weight can be successfully transported from place to place, and particularly objects which have an odd configuration, and which cannot readily be moved by conventional portable hoist structures, or which by their weight would tend to over-balance such structures.

From the foregoing description it will be readily seen that I have produced such a device as substantially fulfills the objects of the invention as set forth herein.

While this specification sets forth in detail the present and preferred construction of the device,

still in practice such deviations from such detail may be resorted to as do not form a departure from the spirit of the invention, as defined by the appended claims.

5 Having thus described my invention, what I claim as new and useful and desire to secure by Letters Patent is:

1. A portable hoist comprising a pair of longitudinally spaced upstanding frame assemblies, 10 said assemblies being wheel supported, a top beam extending between the upper ends of said assemblies, said beam being fixed to one assembly and pivotally connected to the other assembly for relative horizontal swinging movement, a hoist unit secured to and depending from the top beam, a tractor, a horizontally swivelling draft connection between the tractor and said other frame assembly, a power winch on the tractor, and an actuating cable connected between said winch and the hoist unit; the hoist unit comprising a block and tackle unit, said cable being the pull lead of said unit, and direction-changing sheaves mounted between said unit and the power winch.
2. A portable hoist comprising, in combination, a mobile elevator which includes an upstanding elevator frame assembly and a tractor disposed ahead of and connected in draft relation to said elevator frame assembly; an upstanding wheel supported hoist frame assembly 30 disposed rearwardly of said elevator frame assembly, said hoist frame assembly including in rigid relation a forwardly projecting top beam, means detachably pivoting said beam at its forward end in connection with the upper end portion of the elevator frame assembly for relative horizontal swinging movement, a hoist unit depending from said beam, and actuating means connected between the tractor and said hoist unit.
3. A portable hoist as in claim 2 in which said elevator frame assembly includes a vertically movable elevator frame; said pivot means comprising a vertical pin fixed on the upper end 45 of said frame and the beam being formed with a socket into which said pin removably projects from below.
4. A portable hoist comprising, in combination with a mobile elevator which includes an upstanding elevator frame assembly, a tractor disposed ahead of said elevator frame assembly and a horizontally swivelling draft connection between the tractor and frame, the tractor including a power winch at the rear; an upstanding wheel supported hoist frame assembly 55 disposed rearwardly of said elevator frame assembly, said hoist frame assembly including in rigid relation a forwardly projecting top beam, means detachably pivoting said beam at its forward end in connection with the upper end portion of the elevator frame assembly for relative horizontal swinging movement, a block and tackle hoist unit secured to and depending from the top beam, and an actuating cable connected 60 between the power winch and said hoist unit.
5. A portable hoist comprising, in combination with a mobile elevator which includes an upstanding frame assembly, a tractor disposed ahead of said elevator frame assembly and a horizontally swivelling draft connection between the tractor and frame, the tractor including a power winch at the rear; an upstanding wheel supported hoist frame assembly disposed rearwardly of said elevator frame assembly, said hoist frame assembly including in rigid relation 70

a forwardly projecting top beam, means detachably pivoting said beam at its forward end in connection with the upper end portion of the elevator frame assembly for relative horizontal swinging movement, a block and tackle hoist unit secured to and depending from the top beam, and an actuating cable connected between the power winch and said hoist unit; there being direction changing sheaves mounted close to the vertical axis of the swivel draft connection and the vertical axis of the beam pivot, and said actuating cable passing over said sheaves between the winch and said hoist unit.

6. A portable hoist comprising, in combination,

a mobile elevator which includes an upstanding elevator frame assembly and a tractor disposed ahead of and connected in draft relation to said elevator frame assembly, an upstanding wheel supported hoist frame assembly disposed rearwardly of said elevator frame assembly, said hoist frame assembly including, in rigid relation, a forwardly projecting top beam, means detachably connecting said top beam at its forward end with the upper end portion of the elevator frame assembly, a hoist unit depending from said beam and actuating means for said hoist unit.

ROBERT G. LE TOURNEAU.
